CLAIM

The ornamental design for a decoupler tool, as shown and described.

DESCRIPTION

FIG. 1 is a top side perspective view of an embodiment of a decoupler tool.

FIG. 2 is a top view of the decoupler tool of FIG. 1.

FIG. 3 is a bottom view of the decoupler tool of FIG. 1.

FIG. 4 is a first side view of the decoupler tool of FIG. 1.

FIG. 5 is a second side view of the decoupler tool of FIG. 1.

FIG. 6 is a first end view of the decoupler tool of FIG. 1.

FIG. 7 is a second end view of the decoupler tool of FIG. 1.

FIG. 8 is a top side perspective view of another embodiment of a decoupler tool.

FIG. 9 is a top view of the decoupler tool of FIG. 8.

FIG. 10 is a bottom view of the decoupler tool of FIG. 8.

FIG. 11 is a first side view of the decoupler tool of FIG. 8.

FIG. 12 is a second side view of the decoupler tool of FIG. 8.

FIG. 13 is a first end view of the decoupler tool of FIG. 8.

FIG. 14 is a second end view of the decoupler tool of FIG. 8.

FIG. 15 is a top side perspective view of an embodiment of a decoupler tool.

FIG. 16 is a top view of the decoupler tool of FIG. 15.

FIG. 17 is a bottom view of the decoupler tool of FIG. 15.

FIG. 18 is a first side view of the decoupler tool of FIG. 15.

FIG. 19 is a second side view of the decoupler tool of FIG. 15.

FIG. 20 is a first end view of the decoupler tool of FIG. 15.

FIG. 21 is a second end view of the decoupler tool of FIG. 15.

FIG. 22 is a top side perspective view of another embodiment of a decoupler tool.

FIG. 23 is a top view of the decoupler tool of FIG. 22.

FIG. 24 is a bottom view of the decoupler tool of FIG. 22.

FIG. 25 is a first side view of the decoupler tool of FIG. 22.

FIG. 26 is a second side view of the decoupler tool of FIG. 22.

FIG. 27 is a first end view of the decoupler tool of FIG. 22; and,

FIG. 28 is a second end view of the decoupler tool of FIG. 22.

The broken lines are directed to environment and are for illustrative purposes only; the broken lines form no part of the claimed design.
